UNITED STATES PATENT OFFICE.

WILLIAM A. CULHANE, OF DETROIT, MICHIGAN.

NAIL-HOLDER.

1,152,301.

Specification of Letters Patent. Patented Aug. 31, 1915.

Application filed February 1, 1915. Serial No. 5,423.

To all whom it may concern:

Be it known that I, WILLIAM A. CULHANE, a citizen of the United States of America, residing at Detroit, in the county of Wayne and State of Michigan, have invented certain new and useful Improvements in Nail-Holders, of which the following is a specification, reference being had therein to the accompanying drawings.

10 This invention relates to a nail holder, and the primary object of my invention is to provide a novel container or receptacle for nails, as shingle nails, and to furnish the container or receptacle with novel means 15 for arranging the nails in a predetermined position relative to each other so that they may be readily withdrawn for use, head up, permost, saving the time usually employed in turning a nail to properly present the 20 point and the head previous to driving the nail.

Another object of my invention is to furnish a nail holder with a vibratory delivery spout wherein novel means is employed to 25 prevent nails from becoming accidentally displaced.

A further object of my invention is to provide a simple and durable nail holder that can be easily attached to the body to 30 support the holder in a convenient position whereby nails can be expeditiously obtained, and with the holder filled with nails, the withdrawal of one nail vibrates a portion 35 of the holder to that extent that other nails are automatically fed into position.

A still further object of my invention is to provide a simple and inexpensive nail holder that embodies a partitioned container or receptacle and a vibratory detachable delivery spout, the latter being easily removed 40 should the container or receptacle become clogged.

The above are a few of the objects accomplished by the novel construction, combination and arrangement of parts to be herein-after specifically described and then claimed, and reference will now be had to the drawings, wherein—

Figure 1 is a perspective view of a nail 50 holder with a portion of the delivery spout removed; Fig. 2 is a perspective view of a detached lid adapted to form part of the delivery spout; Fig. 3 is a side elevation of the nail holder; Fig. 4 is a vertical cross 55 sectional view of the same; Fig. 5 is a longi-

tudinal sectional view of the nail holder, partly in elevation; Fig. 6 is a side elevation of a portion of a nail holder, partly broken away and partly in section; Fig. 7 is a perspective view of a detached delivery spout, 60 and Fig. 8 is a cross sectional view of the same with the lid or cover applied thereto.

In describing my invention by aid of the views above referred to, I desire to point out that I intend the same as merely illustrative of an example whereby my invention may be applied in practice, and I do not care to limit the invention to the precise construction and arrangement of parts shown. The following description is therefore to be broadly construed as including substitute arrangements and constructions of parts which are the obvious equivalents of those to be hereinafter referred to.

In the drawings, the reference numeral 1 75 denotes a breast plate that is substantially triangular in elevation and convexo-concave whereby it will conform to the chest or breast of the wearer's body, and in order that the holder can be conveniently attached to the body, the upper edge of the breast plate, at the ends thereof, has loops or eyes 2 adapted to accommodate a neck strap (not shown), while the lower edge of a breast plate has loops or eyes 3 to accommodate 80 a waist strap not shown.

4 denotes a semi-cylindrical shell which has the lower end thereof partially closed by converging walls 5, said walls being inclined toward the bottom of the shell to 90 provide a slot 6. The edges of the shell 4 and the inclined walls 5 are soldered or otherwise connected to the breast plate 1 and similarly secured within the shell 4, is a deflector 7 having inclined yieldable walls 8 95 extending in proximity to the walls 5 and providing oblong openings or slots 9 between the inclined walls 5 and the lower edges of the walls 8. The deflector is only secured at its top and serves as a partition 100 and divides the shell into two apartments or containers 10 for nails, which are fed through the slot 9 and which provide a heap of nails at the slot 6; the deflector or partition 7 being hollow, to permit of a mass 105 of nails accumulating at the slot 6.

11 denotes resilient arms at the outer sides of the inclined walls 5 and substantially in parallelism with the lower edges thereof. These arms are preferably made of wire 110

looped, as at 12, and soldered or otherwise connected to the breast piece 1, as at 13.

14 denotes a detachable delivery spout or trough that is V shaped in cross section 5 and the longitudinal edges thereof rolled or flanged, as at 15 to rest upon the resilient arms 11, the resiliency of said arms retaining the walls of the spout firmly in engagement with the walls 5 of the shell 4. The 10 spout 14 has the bottom thereof provided with a longitudinal nail slot 16, said slot extending into an inclined outer end wall 17 of the spout and terminating in a nail opening or exit 18.

15 The nail slot 16 extends to the inner end of the spout or trough and to maintain the V shape formation of the spout and prevent the inner ends of the same from spreading, the inclined walls of the spout are connected 20 by a stiffening wire 19 and this wire serves another purpose in conjunction with the looped portion 12 of the arms 11. By reference to Fig. 3 of the drawings it will be observed that the stiffening wire 19 engages 25 behind the looped portions 12 of the arms, said looped portions serving functionally as catches or a hold-fast means for preventing accidental displacement of the spout or trough, particularly when vibrated. In 30 placing the spout in position, the stiffening wire 19 rides under the looped portions 12 and as these looped portions are resilient, said looped portions readily spring into position to hold the spout beneath the shell 4 35 and in communication with the slot 6 formed by the walls of said shell.

20 denotes a closure carried by the outer end of the rigid arm 21 soldered or otherwise connected to the shell 4 and said closure 40 is adapted to normally close the opening or exit 18 and prevent nails from accidentally falling out of the spout or trough 14.

22 denotes a lid or cover for the outer end of the spout or trough, and by reference to 45 Fig. 8, it will be observed that the longitudinal edges of the lid are rolled or reamed to engage the longitudinal edges of the spout. The lid or cover slides upon the outer end of the spout and abuts the shell 4.

50 When a nail is removed from the spout or trough, said spout yields and is slightly lowered as a nail is shifted to the opening or exit 18 and with the spout lowered, as shown in Fig. 5, the closure 20 does not in-

55 terfere with the withdrawal of the nail. As soon as the nail passes out of engagement with the spout, said spout is vibrated and assumes its normal position with the closure 20 over the opening or exit 18. Vibration of

60 the spout causes nails to enter the spout and assume a suspended position in the slot 16, said nails being suspended by the heads thereof, as clearly shown in Figs. 1 and 5. Irrespective of the manner in which the 65 nails are placed in the compartments or

containers, the nails eventually reach the spout and assume a position relative thereto that permits of easy withdrawal of a nail.

I attach considerable importance to the vibratory spout, since it is practically impossible for the nail holder to become clogged and inoperative for the purposes for which it is intended, besides the closure for the exit opening of the nails prevents waste without interfering with ready withdrawal of a nail. As a nail is withdrawn from the spout, the spout rebounds to normal position and jars the walls 8 of the deflector, consequently nails are fed toward the spout, and with the spout detachable it is an easy matter to substitute spouts that will accommodate nails of various sizes.

The nail holder possesses other advantages that will be apparent to carpenters and other artisans.

What I claim is:—

1. A nail holder comprising a breast plate, a receptacle carried thereby and adapted to contain nails, and a vibratory delivery spout supported at one end and arranged to extend laterally from said receptacle and to receive nails from said receptacle and support the same for ready removal from said spout.

2. A nail holder comprising a receptacle 95 adapted to contain nails, a vibratory spout carried thereby and provided with a nail exit, and means carried by said receptacle arranged normally to close the exit of said spout.

3. A nail holder comprising a breast-plate, a receptacle carried thereby and adapted to contain nails, a detachable vibratory delivery spout carried by said receptacle and adapted to receive nails therefrom and support the same for ready removal, and means fixed relatively to said spout and arranged to prevent accidental displacement of nails therefrom.

4. A nail holder comprising a breast 110 plate, a receptacle carried thereby and adapted to contain nails, a deflector in said receptacle, a detachable delivery spout in communication with said receptacle and adapted to support nails for ready removal therefrom, and means engaging the sides of said spout for yieldably supporting said spout relatively to said receptacle.

5. A nail holder comprising a receptacle 120 adapted to contain nails, a deflector therein, a delivery spout in communication with said receptacle and provided with a nail exit, means in said spout normally closing the exit thereof, and means for holding said spout so arranged that said spout can be shifted relatively to the exit closing means.

6. A nail holder comprising a receptacle adapted to contain nails, a delivery spout in communication with said receptacle and provided with a nail exit, a closure in said spout 125

normally closing the nail exit thereof, and means holding said spout relatively to said receptacle so arranged that said spout can be shifted relatively to said closure.

- 5 7. A nail holder comprising a breast plate, a receptacle carried thereby and having the bottom thereof provided with a slot, means in said receptacle adapted to deflect nails through said slot, a vibratory spout 10 detachably connected to said receptacle and arranged to receive nails from the slot thereof, said spout having a nail exit at one end thereof, and means fixed relatively to said spout and normally closing the exit thereof.
- 15 8. A nail holder comprising a breast plate adapted for attachment to the wearer's body, a receptacle carried thereby, a deflector in said receptacle, a vibratory delivering spout detachably connected to said receptacle and 20 arranged to receive nails therefrom and support nails in a suspended position for ready

removal from said spout, said spout having an end thereof provided with a nail exit, a closure carried by said receptacle and normally closing the nail exit of said spout, and 25 a detachable cover for said spout.

9. A nail holder comprising a receptacle adapted for attachment to the wearer's body, resilient arms carried thereby, a delivery spout supported by said arms and detachably held in engagement with said receptacle by portions of said arm, said spout having a nail exit, and a closure in said spout fixed relatively thereto and adapted to normally close the nail exit of said spout. 30 35

In testimony whereof I affix my signature in presence of two witnesses.

WILLIAM A. CULHANE.
